SEGMENTING MACHINE FOR DRY ICE

Granville G. Westerfield, Indianapolis, Ind.

Application May 8, 1939, Serial No. 272,440

5 Claims. (Cl. 143—26)

The object of my invention is to provide mechanism by which blocks of solidified carbon dioxide may be conveniently and safely cut into uniform smaller pieces of desired size and automatically packaged in a package comprising a series of connected pockets, the construction of the package being such that an appropriate number of connected pockets filled with uniform pieces of dry ice may be used as a wrapper or envelope for an article to be refrigerated. The package mentioned above forms the subject matter of my co-pending application Serial No. 272,439.

The handling of dry ice involves some danger, because of its very low temperature, and my improved mechanism has been so designed as to eliminate the necessity of manual manipulation of the dry ice from its transition from an integrated portion of the supply block to the interior of the package in which it may be readily and safely transported and manipulated to form envelopes for articles to be refrigerated.

The accompanying drawings illustrate embodiments of my invention:

Fig. 1 is a plan of the machine, but showing only a fragment of the package-strip and omitting parts of the feeding mechanism for the package-strip;

Fig. 2 is a front elevation in partial vertical section;

Fig. 3 an elevation and partial vertical section, on a larger scale, of the right hand end of the machine with the package-strip and its supporting table omitted;

Fig. 4 a fragmentary vertical section on line 4—4 of Fig. 1, on an enlarged scale; and

Fig. 5 a fragmentary elevation of the feeding mechanism for the package-strip.

In the drawings 20 indicates a main frame having horizontal tracks 21—21 extending from front to rear of the main frame. Mounted on these tracks is a carriage 22 in which is journaled a shaft 23 upon which are pivoted two depending arms 24—24, each of which is axially slidable in a pocket 25 at the upper end of a swinging arm 26. The arms 26 are connected to a rock shaft 27 provided, at one end, with a lever 28 to which is connected a pitman 29, the opposite end of which is adjustably connected to a wrist pin plate 30 carried by a shaft 31, the arrangement being such that rotation of shaft 31 will cause reciprocation of rock shaft 27 and the lever arms 26 and consequent reciprocation of carriage 22 on its tracks 21.

Carriage 22 is provided with sideboards 32 to form a runway or receptacle for a block of dry

ice 33 and the floor of the carriage, between the sideboards, is slotted at 34 above and parallel with shaft 23. Shaft 23, at its middle and for the major portion of its length, is provided with a quickpitch thread 23' embraced by a nut 35 slidably mounted in slot 34 and carrying a pusher plate 36 adapted to engage the rear end of block 33. The pusher plate 36 is provided with a suitable handle 37 and the nut 35 is preferably a split nut or half-pocket nut of well known form, such that it may be readily disengaged from the quickpitch screw 23' for rapid return movement toward the right, Fig. 2. Nuts of this general type are well known in slicing machines of various kinds, such as meat slicing machines, and therefore need no detailed illustration.

Secured to shaft 23 is a ratchet wheel 38 engaged by a pawl 39 carried by a bell crank lever 40 journaled on the shaft adjacent the ratchet wheel and provided with a depending weighted arm 40' intermittently engaged by a stop 41 carried by the main frame and connected by a linkage 42 to a lever 43 pivoted at 44 on the main frame and swingable relative to detent segment 45 to adjust the stop 41 toward or from the plane of the axis of shaft 23 to contact lever arm 40' at a greater or lesser distance from the axis of shaft 23 so as to vary the amount of advancement of shaft 23 for each reciprocation of carriage 22 and thereby vary the amount of advancement of the pusher plate 36 and consequent advancement of the ice block 33.

Coordinated with the delivery end of carriage 22 is the active run of a band saw 50 mounted to act in the vertical plane at right angles to the line of movement of pusher plate 36. The band saw 50 is passed around a driving wheel 51 and idler 52, in the usual manner. The shaft of wheel 51 is connected by worm gearing 53 with a shaft 54 parallel with shaft 31 and provided with a clutch 55 by means of which the gearing 53 may be connected to, or disconnected from, shaft 54.

Movement of carriage 22 away from the observer (upwardly in Fig. 1) brings block 33 into engagement with the band saw 50 to cut a slab of desired thickness from the left hand end of block 33 and to bring said slab, at the time of its complete severance, opposite a flipper finger 61 which is spring pivoted on a vertical axis 62 and is somewhat above the vertical center of block 33. Continued advancement of carriage 22 away from the observer brings the left hand end of the forward sideboard 32 into engagement with one arm of a spring-biased bell crank lever

64, pivoted at 65, so that its opposite arm will engage finger 61 to move it so as to unbalance the severed slab and cause it to fall upon a horizontal slotted plate 66 over which are mounted the two saws 67—67 carried by the horizontal shaft 68. The saws 67 are arranged to cut each slab into three equal strips, and the slab, after severance, is advanced into engagement with the saws 67 and therebeyond by pushers 79 mounted in the slots of plate 66 and carried by a carriage 71 mounted in a track 72. Pivoted upon carriage 71, at 73, is a depending rod 74 slidably mounted in a pocket 75 formed in the upper end of a lever 76 carried by a rockshaft 77. Lever 76 is provided with a swiveled eye 78 through which slides a rod 79 pivoted, at 80, on one of the levers 26. Rod 79, upon opposite sides of eye 78, is provided with adjustable stop blocks 81—81, the arrangement being such that, toward the end of each half reciprocation of arms 26, the stop blocks 81 will alternately engage lever 76 to cause reciprocation of the pusher heads 70 in their runways.

Tracks 90—90, at right angles to tracks 21, support three channel-shaped carriages 91, 91', 91'', so proportioned and arranged as to be capable of receiving the strips of dry ice produced by saws 67. In order to align these channel-shaped carriages 91, 91', 91'' in a position to receive the strips, as they are formed by saws 67, and to later position these channel carriers for delivery of their contained strips into my improved package, to be described, the carriages 91, 91', 91'' are connected, respectively, to the outer ends of pitmans 92, 92', 92'' connected to a lever 93, at different points in the length of said lever, whereby, upon reciprocation of said lever, differential attachment of the pitman to said lever will carry the several carriages 91, 91', 91'' to advanced positions, indicated in dotted lines in Fig. 1, where they are separated from one another to a greater extent than when in their receiving position, indicated in full lines.

Lever 93 is reciprocated by a pitman 95 connected to a wrist pin plate 96 carried by shaft 97 having a gear 98 coacting with a gear 99 carried by shaft 54, the gears 98 and 99 being of the well known intermittent type such that one rotation of shaft 54 produces one rotation of shaft 97 followed by a period of rest.

My improved package is composed of endless strips of corrugated paper 100, and associated corrugated liner paper strip 101 and an associated cover strip 102, thereby providing a plurality of parallel connected, open-ended pockets 103 sized to receive the strips of material produced by saws 67. The several sheets of which the package is composed are united by adhesive at the ridges 104 between the pockets 103. An endless strip of this multi-pocket package traverses a work table 110 which is parallel with the tracks 90 and in the region of the movement of the channel carriers 91, 91', 91''. The work table 110 is overlaid by a lip 111 (Fig. 4), beneath which the adjacent edge of sheet 102 of the package passes while the adjacent edge of sheet 101 of the package passes over the lip so that the mouths of pockets 103 are thereby vertically aligned with the delivery ends of the channel carriers 91, 91', 91''.

The package strip is intermittently advanced three pockets at a time by a pusher bar 120, the free end of which rides upon the package strip and is provided with depending fingers 121 adapted to engage the rear wall of every third

5 pocket 103. Pusher bar 120 is carried by an arm 122, carried by a rockshaft 123, provided with an operating arm 124 slotted at its lower end to adjustably receive one end of a pitman 125 connected to the upper end of lever 93', the arrangement being such that each forward movement of lever 93 to shift the channel carriages 91, 91', 91'' from receiving positions to delivering positions will come at the same time and advance the package strip three pockets and align three empty pockets with the channel carriers 91, 91', 91'' in their delivery positions.

Arranged above the plane of table 66 in alignment with the delivery positions of the channel carriers 91, 91', 91'' are three pusher fingers 130, each of which is adapted to traverse one of the carriers 91, 91', 91''. Each pusher finger 130 is provided with an upwardly projecting pivoted stem 131 slidably mounted in a pocket 132 formed in the lower end of a lever 133. The several levers 133 are carried by rockshaft 134 having a bell crank lever 135, one arm of which is connected to a spring 136 anchored at 137 on the main frame and arranged to bias the rockshaft to normally position the several pusher fingers 130 just beyond the receiving ends of the carriers 91, 91', 91'' in their delivery positions.

20 The other end of lever 135 is provided with a roller 135' which is overridden by an arm 138 pivoted at 139 to carriage 22. At an intermediate point in its length, the arm 138 is provided with a notch 140 formed to hook over roller 135' to move bell crank lever 135 in opposition to spring 136, so as to project the pusher fingers 35 130 through the carriers 91, 91', 91'' an amount sufficient to deliver the ice strips from the carriages into the package strip, whereupon a roller 141 carried by the arm 138 comes into engagement with fixed cam 142, carried by the standards which support shaft 134, to release the pusher fingers 130 for return to normal position by spring 136 and to permit further movement of carriage 22 toward the front of the machine without movement of bell crank lever 135.

40 The shaft 51' of wheel 51 is driven from any suitable source of power and shaft 51' is connected by pulley 143, belt 144, and pulley 145 with shaft 68.

50 I claim as my invention:

1. In a machine for segmenting blocks of material such as dry ice, a band saw and associated material-supporting table, a block carrier reciprocable in a plane parallel with one run of the saw, an element having a slab-engaging portion 55 movable in a plane intersecting the sawing plane and arranged to engage one vertical face of a slab segmented from the block by the saw above its center of gravity, and means synchronized with the block carrier for actuating said element toward the sawing plane, subsequent to slab segmentation, for overbalancing the slab to a recumbent position on the material-supporting table.

65 2. In a machine for segmenting blocks of material such as dry ice, a band saw, a block carrier reciprocable in a plane parallel with one run of the saw, an element arranged to engage a slab of material, segregated by the saw, and overbalance it to a recumbent position, a table arranged to support the recumbent slab, slab cutting means arranged in position to cut slabs into strips when propelled over said table, slab propelling means arranged to engage a recumbent slab and propel it through said cutting means.

and means synchronized with the block-carrier for reciprocating said slab propelling means.

3. In a machine for segmenting blocks of material such as dry ice, a band saw, a block carrier reciprocable in a plane parallel with one run of the saw, an element arranged to engage a slab of material, segregated by the saw, and overbalance it to a recumbent position, a table arranged to support the recumbent slab, slab cutting means arranged in position to cut slabs into strips when propelled over said table, slab propelling means arranged to engage a recumbent slab and propelling against said cutting means, means synchronized with the block-carrier for reciprocating said slab propelling means, said means comprising a lever connected to the block-carrier, a lever connected to the slab propelling means, and a connecting rod between said levers having two opposed one-way contacts between the connecting rod and the slab propelling lever, whereby the block-carrier, at the initial end of its movement in either direction may move independently of the slab propelling means.

4. In a machine for segmenting blocks of material such as dry ice, a band saw, a block carrier reciprocable in a plane parallel with one run of the saw, feeding means associated with the carrier for intermittently feeding the content of the carrier toward the plane of said run of the saw, means for reciprocating said carrier, means synchronized with said reciprocating means for intermittently actuating said feeding means while

the carrier is laterally offset relative to the saw, a pusher laterally offset relative to the saw in position to engage a slab severed from the carrier content above its center of gravity, means synchronized with the carrier reciprocating means for actuating said pusher to overturn said slab to a recumbent position, and a support arranged to receive and support said overturned slab.

5. In a machine for segmenting blocks of material such as dry ice, a band saw, a block carrier reciprocable in a plane parallel with one run of the saw, feeding means associated with the carrier for intermittently feeding the content of the carrier toward the plane of said run of the saw, means for reciprocating said carrier, means synchronized with said reciprocating means for intermittently actuating said feeding means while the carrier is laterally offset relative to the saw, a pusher laterally offset relative to the saw in position to engage a slab severed from the carrier content above its center of gravity, means synchronized with the carrier reciprocating means for actuating said pusher to overturn said slab to a recumbent position, a support arranged to receive and support said overturned slab, slab segmenting means arranged in advance of the overturned slab, a slab pusher, and means synchronized with said carrier for driving said slab pusher to carry the slab through said segmenting means.

GRANVILLE G. WESTERFIELD.
